UNITED STATES PATENT OFFICE.

JOSEPH W. GUNTHER, OF PORTLAND, OREGON.

SCREW-PROPELLER.

1,035,003.

Specification of Letters Patent.

Patented Aug. 6, 1912.

Application filed October 24, 1911. Serial No. 686,377.

To all whom it may concern:

Be it known that I, JOSEPH W. GUNTHER, a citizen of the United States, residing at Portland, in the county of Multnomah and State of Oregon, have invented new and useful Improvements in Screw-Propellers, of which the following is a specification.

The invention relates to propellers, and more particularly to the class of screw propellers for boats or other water crafts.

The primary object of the invention is the provision of a propeller in which a positive grip will be attained upon the water, so as to advance the boat, without causing any appreciable unsteadiness in the travel or advancement of the boat, or in any way impeding the same.

Another object of the invention is the provision of a propeller which will enter and leave the water, with resistance, and that will possess full driving power, without the possibility of the loss of energy or its hold upon the water while in action, thereby assuring high speed in the propulsion of the boat for the advancement of the same.

A further object of the invention is the provision of a propeller of this character which is simple in construction, thoroughly reliable and efficient in operation, and inexpensive in manufacture.

With these and other objects in view, the invention consists in the construction, combination and arrangement of parts, as will be hereinafter more fully described, illustrated in the accompanying drawings, and pointed out in the claim hereunto appended.

In the drawings: Figure 1 is a fragmentary side elevation of a boat, showing the propeller in position relative thereto and constructed in accordance with the invention. Fig. 2 is an end elevation of the propeller. Fig. 3 is a vertical longitudinal sectional view through the same. Fig. 4 is an enlarged side elevation of the propeller.

Similar reference characters indicate corresponding parts throughout the several views of the drawings.

Referring to the drawings by numerals, 5 designates a portion of the hull of a boat, and 6 the propeller shaft which is operated from an engine or turbine (not shown), of any improved type, the propeller shaft being mounted in the hull of the boat in the usual manner, and projects outwardly therefrom at the stern of the said hull, as

usual, and has fixed thereto a propeller, presently described.

The propeller comprises a spiral blade 7, the same being spirally arranged about the propeller shaft 6, and has its inner edge notched, as at 8, to form tongues 9, the same being outbent and having passed therethrough suitable fasteners 10, thereby securing the blade to a hub 12. The ends 60 of the blade 7 are rounded, as at 11, and extend past each other, so as to be disposed in overlapping relation relative to the axis of rotation of the shaft 6. The rounded ends 11 of the blade 7 will permit the same 65 to enter the water without impeding the rotation of the blade or causing the feathering of the blade upon the water, during the rotation of the same.

Formed at or fixed to the outer edge of 75 the blade 7, and coextensive with the greater portion of the trend of the same, is an out-turned flange 13, the same being gradually tapered outwardly, as at 14, toward the ends thereof from a medial point of the same, the 80 flange 13 being designed to hold the water against the blade 7 while rotating and prevent the dispersing of the water laterally when the blade is rotating therein, thus assuring a positive impact of the blade against 85 the water while active for advancing the boat, without perceptible unsteadiness in the forward travel thereof, or impeding its movement. The flange 13, which has its ends terminating at the point of the rounded 90 ends of the blade 7, by reason of its tapered portions 14, will enter and leave the water without interfering with the rotation of the blade therein or resisting the driving energy of the engine or turbine operating the propeller shaft. Furthermore the flange 13 will enable the blade to grip and hold the water during the rotation of the blade and cause it to exert maximum force against the same, whereby a uniform and high speed 95 may be attained for advancing the boat. The hub 12 may be formed integral with the blade 7, and is secured to the shaft 6 in any desirable manner.

From the foregoing, taken in connection 105 with the accompanying drawings, it is thought that the construction and operation of the invention will be readily understood, without requiring a more extended explanation.

What is claimed is:

A propeller of the class described, com-

prising a spiral blade having its ends disposed in overlapping relation to the axis of rotation thereof and also provided with rounded edges, and an outturned flange at 5 the outer edge of the blade, the said flange being tapered in reverse directions from a medial point thereof toward its ends, the ends of the flange merging in the rounded

edges of the blade, and a hub located centrally of the blade and carrying the same. 10

In testimony whereof I affix my signature in presence of two witnesses.

JOSEPH W. GUNTHER.
